FRANCIS L. HAGADORN, OF BALTIMORE, MARYLAND.

Letters Patent No. 90,943, dated June 8, 1869:

IMPROVEMENT IN PINKING-MACHINES.

The Schedule referred to in these Letters Patent and making part of the same.

To all whom it may concern:

Be it known that I, FRANCIS L. HAGADORN, of the city of Baltimore, in the State of Maryland, have invented a new and improved Method of "Pinking" or ornamenting the edges of leather, cloth, silk, and other fabrics; and I do hereby declare that the following is a full and exact description thereof, reference being had to the accompanying drawings, and to the letters of reference marked thereon.

The nature of my invention consists in providing a circular knife, A, corrugated into any given figure, and adjusted by the screws I I in the frame C C O, so as to ply upon the wheel B.

The circular knife A and the cog-wheels G H, are secured between the two slides D D.

The crank E is attached to the axle of the cog-wheel G.

The feeding-board F is secured to the frame by a pin and screw, and the table-screw K holds the entire machine to the top of any ordinary table-shelf or work-bench.

To enable others skilled in the art to make and

use my invention, it is only necessary to add that power may be given to it by means of belts and pulleys, instead of the crank E; that the shaft L L may be indefinitely extended, and the circular knife A duplicated to any desired extent, and arranged upon it.

The knife A and the wheel B are also capable of a vibratory movement, although not shown in the accompanying drawings.

The knife A should be made of superior steel, and the wheel of wood, lead, copper, or other soft material.

What I claim as my invention, and desire to secure by Letters Patent, is—

The corrugated circular knife A, or its equivalent, secured and adjusted substantially in the manner hereinbefore described, and for the purposes herein set forth.

F. L. HAGADORN.
